UNITED STATES PATENT OFFICE.

PETER A. PERSE, JR., OF PUEBLO, COLORADO.

SHADE-ROLLER FIXTURE.

Application filed April 14, 1921. Serial No. 461,186.

To all whom it may concern:

Be it known that I, PETER A. PERSE, Jr., a citizen of the United States, residing at Pueblo, in the county of Pueblo and State of Colorado, have invented certain new and useful Improvements in Shade-Roller Fixtures; and I do hereby declare the following to be a full, clear, and exact description of the invention, such as will enable others skilled in the art to which it appertains to make and use the same.

The invention relates to shade rollers and more particularly to the fixtures cooperating therewith, whereby the shade may be raised or lowered and made secure in the required adjusted position by proper manipulation of a cord.

The invention obviates the usual spring roller and the objectionable features incident thereto, such as the tugging at the shade when it is required to effect a winding thereof or to hold the same in the desired adjusted position, the frequent rapid winding of the shade when released which causes the stick in the lower end of the shade to wedge between the roller and the window frame, or the failure of the shade to wind when fully unwound from the roller.

The present invention insures an even winding of the shade on the roller, prevents tearing of the shade and insures a steady winding or unwinding thereof accordingly as the operating cord is manipulated and enables the shade to be instantly released for unwinding and instantly fastened when adjusted to the required position.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is a front view of the upper portion of a window provided with a shade roller embodying the invention.

Figure 2 is a front view of the shade roller fixture showing the parts on a larger scale,

Figure 3 is a longitudinal section of the fixture,

Figure 4 is an end view thereof, Figure 5 is a transverse section on the line *x-x* of Figure 2,

Figure 6 is a view of the fixture as seen from the inner end,

Figure 7 is a top plan view,

Figure 8 is a detail view of the hanger end of the bracket and a portion of the casing, and

Figure 9 is a detail view of a portion of the roller showing the manner of attaching the shade thereto.

Corresponding and like parts are referred to in the following description and designated in the several views of the drawings by like reference characters.

The numeral 1 designates a window frame, the same being shown to demonstrate the application of the invention. The shade 75 roller is supported at one end by means of a bracket 2 which receives the pin or journal thereof. The opposite end of the shade roller is supported by a fixture which constitutes the subject matter of the present invention. The shade 3 is secured to the roller 4 by means of a strip 5 and a groove 6. The groove 6 extends substantially the entire length of the roller 4 and is provided in a side thereof. An edge portion of the shade 85 3 is pressed into the groove 6 by means of the strip 5, the latter being made secure by means of brads or in any preferred way. The outer side of the strip 5 is flush with the roller 4 to insure a smooth winding of 90 the shade on the roller.

The fixture embodies a bracket 7 which is secured at one end to the window frame 1 in any preferred way. The outer end of the bracket 7 has pairs of lugs 8 on its top side 95 which are spaced apart to receive between them a hanger 9. Projections 10, at opposite sides of the hanger 9, enter the spaces formed between the lugs of the respective pairs. This arrangement holds the hanger 100 9 in predetermined position and admits of the same having the limited movement laterally and longitudinally necessary to the free operation of the shade in the manner later set forth. The casing or frame of the fixture is supported by means of the hanger 9.

The casing or frame is preferably of sectional formation and comprises relatively front and rear sections 11 and 12, respectively. The lower portion of each of the 110 sections 11 and 12 is cut away to form a space or opening 13 when the sections are

properly assembled. The sections 11 and 12 are formed with relatively upper and lower ears 14 and 15, respectively, said ears being transversely apertured to receive bolts or like fastenings whereby the sections are made secure when brought together. The upper ears 14 are received between the depending elements of the hanger 9 and are held thereto by a bolt or fastening 16. The lower ears 15 are connected by bolts 17 or like fastening means.

A spool is rotatably mounted in the casing or frame and comprises a spindle 18 and circular rims or heads 19. The rims or heads 19 fit snugly within end portions of the casing or frame and the meeting portions are annularly grooved to form races to receive balls 20 which provide anti-friction bearings and locking means to hold the spool in proper position. A socket 21 is provided at the inner end of the spool and receives the adjacent end of the shade roller 4 which is secured therein in any manner. Ratchet teeth 22 are disposed at the inner end of the socket 21 adjacent the casing frame and cooperate with a pawl 23 to hold the shade 3 at the required adjusted position.

The pawl 23 preferably forms part of a frame pivotally connected to the casing and comprising a curved arm 24, a straight arm 25 and a tie rod 26. The arms 24 and 25 are spaced apart a distance to receive a casing between them and their free ends are connected by the tie rod 26. The curved arm 24 clears the socket 21 and the ratchet teeth 22 thereon. The upper ends of the arms 24 and 25 are pivotally connected to ears 27 projecting from the rear section 12 of the casing. The ratchet teeth 22 face in a direction to prevent a clockwise movement of the spool when engaged by the pawl 23. This prevents unwinding of the shade 3 and holds the same in the required adjusted position. The pawl 23 is adapted to ride on the ratchet teeth 22 when winding the shade 3 upon the roller 4.

An operating cord 28 is made fast at one end to the spool and passes beneath the tie rod 26. The operating cord 28, after having one end thereof passed through an opening 28a in the spindle 18 and then knotted to prevent its withdrawal, is wound upon the spool in a reverse direction to the winding of the shade 3 on the roller 4. When the shade 3 is fully wound upon the roller 4, the operating cord 28 is practically unwound from the spool with the possible exception of one or two winds. If it be required to lower the shade, the lower portion of the cord 28 is grasped and drawn outward away from the window whereby it is brought into contact with the tie rod 26 and swings the lower end of the pawl frame outwardly whereby to disengage the pawl 23 from the teeth 22, and upon manipulating the cord to

70 permit an upward movement thereof, the shade 3 lowers by unwinding from the roller 4 due to the weight of the stick or bar 29 inserted in the hem formed at the lower end of the shade 3. As the shade 3 lowers by unwinding from the roller 4, the spool is rotated to wind the cord 28 thereon. When the shade reaches the required adjusted position, the cord 28 is moved inward to release the tie rod 26, whereby the pawl frame 75 swings inwardly and brings the pawl 23 into engagement with one of the ratchet teeth 22, whereby the shade is held in the adjusted position. To raise the shade 3, it is necessary only to pull upon the cord 28, whereby it is unwound from the spool and effects a rotation of the roller 4 to wind the shade 3 thereon. During this operation, the pawl 23 rides on the ratchet teeth 22 and upon releasing the cord 28, the shade is instantly 80 held in the adjusted position because of the engagement of the pawl 23 with a ratchet toothed 85 22.

What is claimed is:

1. A shade roller fixture comprising a 90 longitudinally separable casing, a spool mounted within the casing, with the ends of the spool constituting end closures for the casing, the opposing portions of the ends of the spool and the casing being annularly grooved, and balls in the matching grooves forming means to prevent displacement of the spool from the casing and anti-friction bearings.

2. A shade roller fixture comprising a casing including relatively front and rear sections having their lower portions cut away intermediate the ends to form a space when the sections are assembled, fastening means, said sections having outwardly extending apertured ears coacting with said fastening means whereby the sections are made secure, a spool mounted within the casing, with the ends of the spool constituting end closures for the casing, the ends of the spool and casing being annularly grooved, and balls in the matching grooves forming means to prevent displacement of the spool from the casing and anti-friction bearings.

3. A shade roller fixture comprising a casing, a spool mounted within the casing, ratchet teeth carried by the spool, arms pivoted to opposite ends of the casing, one of the arms having a pawl in cooperative relation with the ratchet teeth, a tie rod connecting the free ends of the arms, and an operating cord adapted to wind upon the spool and to directly engage and actuate the said tie rod whereby to disengage the pawl from the ratchet teeth to permit lowering of the shade.

4. A shade roller fixture comprising a sectional casing having its lower portion cut away, a spool mounted in the casing, a socket 120 at one end of the spool, ratchet teeth on

the socket, arms at opposite ends of the casting pivoted thereto, one of the arms being curved and provided with a pawl in cooperative relation with the ratchet teeth, a tie rod connecting the free ends of the arms, and an operating cord adapted to wind upon the spool and directly engageable with said tie rod to disengage the pawl from the ratchet teeth when a lowering of the shade is desired.

5. A shade roller fixture embodying a spool rotatable with the shade roller, an operating cord wound upon the spool in a reverse direction to the winding of the shade on the roller, means cooperating with the spool for holding the shade in the required adjusted position and releasable by said operating cord to admit of lowering of the shade, a bracket, and a hanger forming suspending means for the spool and having loose connection with said bracket to admit of the spool having a limited free movement.

6. A shade roller fixture comprising a bracket embodying pairs of spaced lugs, a hanger suspended from the bracket and having opposed projections entering the spaces between the lugs of the respective pairs, a casing connected with the hanger; a spool mounted within the casing and rotatable with the shade roller, an operating cord wound upon the spool in reverse direction to the winding of the shade on the roller, a ratchet rotatable with the spool, a pawl operable to engage the said ratchet and hold the shade in the required adjusted position, and means operable to release said ratchet from said pawl to admit of lowering of the shade.

In testimony whereof I affix my signature in presence of two witnesses.
